UNITED STATES PATENT OFFICE

BENJAMIN TRAGER, OF BRONX, NEW YORK

BRIEF BAG

Application filed March 3, 1928. Serial No. 258,708.

This invention relates to brief bags and cases and being particularly directed to an article of manufacture which can be cheaply constructed, requiring a minimum amount of labor by dispensing with the usual stitching operations.

One of the objects of my invention is to provide and construct a brief bag or case of any desired type or style, i. e. either one or more pockets, in which the bottom, ends or gussets are reenforced by metallic strips, said strips being attached in such a manner as to dispense with the stitching of the material.

Another object of my invention is to provide a leather or composition brief bag or case with reenforcing end and bottom strips of light metal adapted to be clamped or clinched to the edges of the front and back of the bag or case and to the gussets as well as the bottom of the pockets, thus joining the parts in a manner otherwise performed by a stitching machine.

To enable others skilled in the art to more fully comprehend the underlying features of my invention that the same may be practiced in the construction of brief bags, cases, school bags and analogous articles either of leather or other compositions, reference is had to the accompanying drawing forming a part of and illustrating my invention in which

Fig. 1 is a perspective view showing one type of brief bag or case to which the invention is applied.

Fig. 2 is a similar view showing the relative relation of the front, back, end gusset and strip before it is attached.

Fig. 3 is a fragmentary, end view of a compartment brief bag showing the application of my invention.

Fig. 4 is a section taken substantially on the line 4-4 of Fig. 2.

Referring now to the drawings wherein like reference characters designate corresponding parts throughout the several views, 5 designates the front and 6 the rear face or side of a conventional type of single, dual or multiple pocket or compartment brief bag, case or folio which may be constructed of leather or other suitable composition of ma-

terial. The rear face 6 is provided with an extension or top flap 7 of a length to fold over the open top 8 as is well known. The bag or case may or may not be provided with a lock or other suitable fastening means as manufacturing necessities require.

The bag or case shown in Figs. 1 and 2 is provided with end gussets 9, 10 which may be integral or separable from the bottom and which is usually stitched to the end edges of the front and back 5, 6 and along the bottom by the well known stitching machine.

Instead of stitching the parts of the bag or case together as has been heretofore the practice, I provide a U-shaped bottom and end reenforcing strips 11, 12 preferably of light metal, capable of being stamped and bent by a pressing machine. The strips are of a length to extend along the bottom edges 70 joining the front and rear faces 5, 6 to the bottom, the end strips 12 being somewhat shorter than the bottom strips and joining the end edges of the front and rear faces to the end gussets. The bottom strips are further cut at their ends to form a mitered corner as at 13, thus producing a neat appearance.

Referring particularly to Fig. 4 it will be noted that the metal strips are provided with inwardly struck prongs 14 which may be arranged in staggered relation throughout the length of said strips so that when the pressing and clinching operation is performed, the bottom, end gussets, front and rear faces are firmly joined to produce the pocket of the bag.

While I have shown a continuous strip, U-shaped in cross section, I do not wish to be necessarily limited to the shape of the metal strip joining the parts. If so desired the strip may be provided with a series of tabs 90 also having prongs or other fastening means for clinching the parts of the material together.

In Fig. 3 I have shown my invention carried forward in the construction of a multiple compartment brief bag or case in which a series of strips 15 are provided, joining the gusset to the front, rear face and bottom.

While I have shown and described my invention with some degree of particularity, it

will be realized that other modifications and changes may be resorted to under separate conditions. I therefore do not wish to be limited and restricted to the exact details shown and described but reserve the right to make such changes and illustrations as may fairly fall within the scope of the subject matter now being claimed.

Having shown and described my invention 10 what I claim as new and desire to secure by Letters Patent is:—

1. A brief bag or case of the class described comprising a front face, a rear face having a top flap, end gussets and a bottom and metallic clamping means for joining the edges of the gussets and bottom to the edges of the said front and rear faces, said clamping means extending throughout the height of the gussets and length of the bottom of said bag 20 or case.

2. A brief bag or case of the class described comprising a front face, a rear face, end gussets and a bottom and metallic strips for clamping the edges of the gussets and bottom 25 to the edges of the said front and rear faces, said strips extending throughout the height of the gussets and length of the bottom of said bag or case.

3. A brief bag or case of the class described 30 comprising a front face, a rear face, end gussets, a bottom and metallic strips, U-shaped in cross section for clamping and binding the edges of the gussets and bottom to the edges of the said front and rear faces, said strips 35 extending throughout the height of the gussets and length of the bottom of said bag or case.

4. A brief bag or case of the class described comprising a front face, a rear face having a 40 top flap, end gussets and a bottom and metallic strips, U-shaped in cross section for joining the edges of the gussets and bottom to the edges of the said front and rear faces, said strips extending throughout the height 45 of the gussets and length of the bottom of said bag or case, said strips having prongs for clinching the material to be joined.

5. A brief bag or case of the class described comprising a front face, a rear face having a 50 top flap, end gussets and a bottom, vertical strips joining the end gussets to the side edges of the front and rear faces and horizontal strips joining the bottom edges of the front and rear faces to the said bottom, the meeting ends of certain of said strips being mitered, all of said strips being formed with prongs for clinching the material when said strips are attached.

In testimony whereof I affix my signature.
60 BENJAMIN TRAGER.
